UNITED STATES PATENT OFFICE.

ALFRED E. MEYER, OF CINCINNATI, OHIO.

SIGNAL SYSTEM.

1,375,059.

Specification of Letters Patent. Patented Apr. 19, 1921.

Application filed February 11, 1918. Serial No. 216,561.

To all whom it may concern:

Be it known that I, ALFRED E. MEYER, a citizen of the United States, and residing at Cincinnati, in the county of Hamilton and 5 State of Ohio, have invented a new and useful Improvement in Signal Systems, of which the following specification is a full disclosure.

My invention relates to an electric system for the transmission of signals as of 10 central station alarm service or watchmen's time recording.

The invention has for an object the provision of a signal system with a metallic 15 service line extending from a central or receiving station to the transmitting stations and back to the receiving station, with the transmitters of said transmitting stations in series circuit connection with said metallic 20 line, and with a ground connection under automatic control dividing the transmitting stations into a plurality of service or signal transmitting branch lines, each with an earth return circuit, whereby the advantages of a continuous metallic line between 25 the receiving and transmitting stations is available.

Another object of the invention is to provide a plurality of signal systems for central station alarm service, each system comprising receiving apparatus and transmitting apparatus connected by a metallic partial circuit line and ground return, and a line controlling device in connection with the metallic 30 lines of said systems for establishing the earth return for said metallic lines, automatically operated by a change in current strength from the normal for establishing a metallic line and receiving station connection between the metallic lines of the 35 different systems in the event of an impairment to one of said metallic service lines.

Another object of the invention is to connect the ends of central station metallic partial signal circuit lines, with a circuit controlling device uninfluenced by the normal current strength carried by the circuit lines, but responsive to a definite increase of current strength for bringing a portion of an 40 paired service line into communication with the central station over and in direct circuit with a second normal service line, and for reestablishing the independence of the service lines when the impairment to the 45 one has been rectified.

Other features and objects of the inven-

tion, combination of elements, and arrangement of parts will be more fully hereinafter described, and more particularly pointed out in the claims. A convenient embodiment is typically illustrated in the accompanying drawing, forming a part hereof, and in the drawing like characters of reference denote corresponding parts throughout the several views, of which:—

Figure 1 is a diagrammatic view of an electric signal system with the various appliances connected in electric circuit under a normal condition.

Fig. 2 is a diagrammatic view of a modified form of wiring and circuit controlling apparatus.

As the system primarily is contemplated for a central station night watch time recording or fire alarm signal service, the 75 description will generally be confined to this particular field of use, although as to certain aspects other kinds of electric signal systems are comprehended.

A closed metallic circuit for the transmission of signals may be designated as a continuous line starting from a central station or receiving point, including in series the various and different transmitting devices embraced in the system and returning to the central station. An open earth return circuit is utilized in connection with the metallic line for transmitting trouble signals. This assures normally the transmission of two signals usually distinctive in 90 character from each point or transmitting device, and provides a means for maintaining the system under test, and also a means for transmitting a single or ground circuit signal in the event of a break in the metallic line, dividing the transmitting devices of the series with those on one side of the break using one portion of the metallic line, and those on the opposite side of the break using the other portion of said metallic 95 line. Limitations as to the number of transmitting devices under such system are placed by insurance underwriting authorities, as a precautionary measure.

With my system the advantages above 105 noted in a complete or all closed metallic circuit system are maintained, but the metallic line, when conditions are normal, is divided into independent service lines, each for successively transmitting signals over 110 two independent circuits both having earth return, so that in a single loop line, the

number of subscribers or transmitting devices can be materially increased, and each service line may qualify under the limitation set as to number of transmitting devices.

- Referring to the drawings 1, 1^a, indicate relays for one group of transmitting devices, and 2, 2^a, relays for a second group of transmitting devices, which may be regarded as located in a service station. Relays 1, 2, may be designated as the prime or first relays, and relays 1^a, 2^a, as supplemental or second, the latter having their armatures set so as to require a different or greater current in order to be attracted by their magnet coils over those of relays 1, 2. Thus, under a closed circuit and normal line, relays 1, 2, will stand with their armature levers attracted to their magnets or closed while relays 1^a, 2^a, will stand with these armature levers retracted from their magnets or open. 3 indicates a generator, or source of electric energy supply, and 4, 5, tap key switches for respectively cutting out the relays of the different service lines, and located at the service or receiving station.

The relays represent those of commercial type used in pen recorders, and in general comprise a magnet coil 6, armature lever 7, which as a pole switch, in its to and fro motion, alternately contacts with the relatively opposite terminals 8, 9, for making and breaking electric circuits.

The armature lever is held under tension by a spring 10, which in all relays is arranged, so that its tension may be adjusted or varied.

The tap key switches 4 and 5 are the duplicate of each other, and each comprises a key lever 11, swung between two relatively opposite terminals 12, 13, and under tension by a spring 14 to normally engage or contact with one terminal in this instance terminal 12.

15, 15, 15, represent break wheel signal transmitting devices of one group located at different service points from the service or central station, and may be designated as night watch boxes as of a type of construction, wherein the break wheel is manually started or set in motion by an operator turning a key, and 16, 16, 16, signal transmitting devices of a second group. The number for either group is optional, and in a general way they may be described as switch devices operated by a break wheel, so that one transmitting device is capable of transmitting a signal distinctive over the signal of the other signal transmitting devices. Their operation may also be automatic, as for automatic fire alarm service. For the present purpose, each of the transmitting devices comprises a break wheel 17, flexible switch fingers 18, 19 and 20, each finger having a contact or terminal point

engaging with the contact point of the adjacent finger for completing the circuit through the connected fingers. The finger 18 is extended to engage with the break wheel 17, and its contact point with a registering contact point projected from finger 19, and likewise finger 19 arranged for electrically connecting with the finger 20.

The break wheel 17 is notched or toothed for a proper finger control to transmit in each revolution a definite signal. Each break wheel, under a normal condition of the system rests with the break finger 18 engaging its periphery at a point which will hold the contact point of said finger in engagement with the contact point of an adjacent finger 19 for completing a partial line circuit through said fingers 18 and 19. A third break finger 20, adjacent the break finger 19 normally has its contact point free from engagement with the finger 19 so as not to be in electric circuit therewith. Finger 20 of each call box connects with a wire 21 leading to a ground terminal 22.

At a terminal or meeting point of the metallic service lines 43, each service line including in series wiring the fingers 18 and 19 of each call box or signal transmitting device, a circuit controlling device is provided and operated from the central station over one of the service lines if a break occurs in the other. The controlling device coupling such portion of the broken service line between the point of break and circuit controlling device to the other intact service line to bring it in circuit with the central station, until the trouble of broken service line is rectified.

The circuit controlling device, as shown in Fig. 1, comprises a plurality of flexible fingers 25, 26, 27, and 28, adjacent one another, each mounted upon an insulator base or support. Fingers 25 and 27 are connected together to move as a unit but electrically insulated from one another, with finger 27 having a contact point adapted to connect or engage a contact point of finger 28. Fingers 25 and 26 are arranged to connect with each other through contact points which normally are engaged. 29 indicates a trip lever actuated by a spring 30 after the lever has been tripped by an armature 31 when attracted to its magnet 32. 33 and 34 each indicate a resistance.

Wiring diagram.

The circuits to and from the various terminals of the devices above described may be traced as follows:—

Commencing at the generator or source of electric supply 3, one end of a wire or lead 35 connects with one pole of the generator, and its opposite end connects with the earth at 36. A wire 37 connects to the opposite pole of the generator as a main par-

tial circuit metallic lead line for the various service lines or branches. Each branch or service connects with the main lead line 37 at the central station and may be said to 5 consist of a station line and a field line normally connected by a tap key switch 4. As the different series lines are the duplicate of each other, it is only necessary to describe one in detail, each however running 10 from the central station and terminating at a common point at which the field circuit controller is located so as to connect therewith.

Therefore describing the service line, 15 which includes the relays 1, 1^a, and transmitting device or call boxes 15, it may be said to comprise a station service line 38. The station service line 38 connects at one end with the main lead line 37 and its opposite end with the contact terminal 12 of the tap key switch 4. This station service line 20 38 includes in series circuit connection therewith a resistance 40, and relays 1 and 1^a. The metallic circuit line 39 connects at one 25 end with the key lever 11 of the tap key switch 4 and under normal line condition includes in series circuit connection the fingers 18, 19, of each transmitting device or call box 15 and connects with the resistance 30 33 at its opposite end. From the resistance, metallic circuit line continues through a wire 42 connecting with a terminal 43 as a common terminal for the various metallic circuit lines of the different service branches. 35 The common terminal 43 connects with the one pole of the windings of the magnet 32 and the opposite pole of said magnet windings connect with a wire 44, which extends to and connects with the finger 25 of the 40 circuit controlling device. The circuit thus continues from finger 25, through finger 26, wire 45 to the ground 46. The constant resistance in the service line reduces the 45 current flowing therethrough preventing the full energization of the magnet windings of relay 1^a and magnet 32 of the circuit controller device or an excitation sufficient to attract their respective armatures. Thus closed signal circuits are maintained from 50 the source of electric supply through the said devices in said service lines 38, 39, returning through the earth from the ground terminal 46 to the generator ground terminal 36.

55 For the transmission of a call signal, it may be assumed that the break wheel 17 of a given coil box 15 is rotated, and depending upon its particular signal indicating cut, will, *seriatim*, move the finger 18 to 60 bring the contacts of all fingers 18, 19 and 20 into engagement. This short circuits or shunts the portion of the metallic circuit line from said call box to the ground connection of the circuit controlling device at 65 the end of the line and completes a partial

ground circuit from finger 20 direct to the central station ground terminal, cutting out the resistance 33, causing a rise in the current sufficient to fully energize the windings of the relay 1^a. The armature lever of the 70 relay 1^a is operated for a primary signal indication or recording. The break wheel continuing for a finger control breaks the connection of fingers 18, 19, which breaks or opens the circuit causing the magnet 75 winding of relay 1 to become deenergized for a secondary signal indication or record. Such make and break, in a particular order, commencing and continuing for a double indication or recording of a distinctive signal. 80

The armature 7 of the relay 1^a for the primary signal is operated or vibrated by variations in the current strength through an operating call-box. The armature is 85 attracted to its magnet when the circuit is established through the break fingers 18 and 20 of the operating call-box, connecting the field line or wire 39 and ground return, to which the finger 20 connects. This shunts 90 the resistance 33 resulting in an increase in current strength to relay 1^a and an increase in the degree of its magnet pull, which overcomes the spring normally holding the armature away from its magnet. 95 Instantly upon breaking the contact between the fingers 18 and 20, the circuit is reestablished through the resistance 33, lowering the current strength and thereby the pull of the magnet of relay 1^a, making 100 the spring force prevail over the pull of the magnet to swing the armature to its retracted position. The armature of the relay 1 is normally held attracted to its magnet and for receiving the secondary signals is 105 vibrated by making and breaking the circuit through an operating call-box. The circuit control in a signal transmission is arranged so that the circuit is only broken at the interval when the armature of the relay 1^a is 110 retracted or retracting, otherwise it might interfere with the primary signal indication designated by dots or dashes or a combination of both.

The projections on the code wheels 17 operate to close the circuit to ground through finger 20, while maintaining the circuit through fingers 18, 19, and the depressions permit the opening of the circuit by the movement of finger 18 away from finger 19. 115

Now assume that a break or ground occurs in the circuit line 39, say at a point indicated by the cross, which would be observed at the central station, a break affecting relay 1, which would become deenergized, releasing its armature lever showing that the condition of the field line 39 has been disturbed, a break in the circuit would leave the transmitting devices or call boxes 125 15, 15, beyond such break out of connection 130

with the central station. The operator would thereupon immediately throw the tap key 5 to connect line 39^a in circuit with the line 47, connecting with the lead line 37, 5 and which may also include a resistance 49, but of a less value than the resistance 40, or that commonly in the line, so as to increase the strength of the current in said field service line 39^a for the purpose of fully energizing 10 the windings of magnet 32, the circuit controlling device attracting its armature lever 31, tripping the trip lever 29, which will close or connect fingers 27, 28, and break fingers 25 and 26, thus connecting 15 such portion of the field service line 39 beyond the break X in circuit with the field service line 39^a, as follows:

Commencing with the terminal 50 at the end of the field service line 39^a, through a 20 wire 51, connecting with the finger 28, through said finger 28 connected therewith through said finger 27 and wire 52, connecting with the terminal 53 at the end of the field service line 39, which cuts out the resistance 33 and 34, coupling such broken portion of the field service line 39 with the central station, through a second branch. After the trouble in the service line 39 has been corrected, the trip lever 29 is manually 25 swung and engaged with the armature lever 31, breaking the circuit connection between fingers 27 and 28, and again establishing a circuit connection between fingers 25, 26. The service line for relays 1 and 1^a 30 is likewise provided with a shunt line 54, connecting with the main lead line 37 and adapted to be thrown in circuit with the field service line 39 by the tap key 4, to cut out the relays 1 and 1^a and resistance 40 for operating or energizing the windings of 35 magnet 32 in case of a break in the field service line 39 to throw such portion of the line broken from communication with the central station, in circuit with the field service line 39. A momentary operation of 40 the tap keys 4 and 5 is only necessary for energizing the magnet 32, and to transfer a portion of one service line in circuit with a second service line, so as not to interfere 45 with the sending of signals from the call boxes in communication with the relays of the first branch; or vice versa, as the case may be. Thus, a signal from all the call boxes can be received at the central station. 50 In the diagram, Fig. 2, the circuit controlling or transfer device represents a modified form adapted to be reset from the central station, and in detail comprises the following parts:—

55 The two service branch lines 39—39^a, as in Fig. 1, lead to the circuit controlling or transfer device, with service line 39 connecting with one pole of a magnet winding 32, its opposite pole connecting by a wire 60 to 60 a finger 61, normally as an open line circuit.

The wire 60 through a branch connection connects with the resistance 33, thence by a wire 62 connects with the circuit breaking sector 63 mounted upon a shaft 64 of an ordinary clock movement commonly used in fire 70 or alarm call boxes. A finger 65 normally engages the circuit breaking sector 63 and is grounded. The second service line 39^a connects with one pole of a magnet winding 32^a. The opposite pole of said magnet winding 75 32^a is connected to a wire 66 which leads and connects to a break finger 67 adapted to engage the circuit breaking sector 63. The line 66 connects by a branch with the resistance 34 at one side or pole, while the opposite pole of the resistance connects with the wire 62 leading to the circuit breaking sector 63. 68 represents an armature for tripping the clock movement escapement 69 for releasing the circuit breaking sector 63 80 when either one of the magnet windings 32—32^a have been fully energized to attract the armature 68. Under normal conditions of the system, the circuit in the service line 39 is closed from the central station through 85 said line magnet 32, resistance 33, wire 62, circuit breaking sector 63, break finger 65, returning through the ground. Thus, the resistance 33 is included in the circuit, which reduces the potential to a degree preventing 90 full energization of the magnet winding 32. When it is necessary to transfer or connect the service line 39 with the service line 39^a, a proper tap key at the central office is operated to cut out the resistance and relays 95 connected in the service line 39^a, thus fully energizing magnet 32^a, tripping the escapement and permitting the circuit breaking sector to rotate one-half of the revolution to break the circuit connection between fingers 100 65 and circuit breaking sector 63, and connect the breaking fingers 61 and 67 with the circuit breaking sector 63. In such position of the circuit breaking sector 63 the service line 39 will connect or be coupled to the 105 service line 39^a, through the magnet winding 32, wire 60, contact finger 61, circuit breaking sector 63, contact finger 67, wire 66, magnet windings 32^a to service line 39^a. Under such conditions the resistance 33 and 110 34 will be cut out. The magnet windings 32 and 32^a remain constantly in circuit with the service line communicating with the central office for test and reset purposes, which, as soon as the line conditions have been corrected, either one of the tap keys may be operated to throw in a higher potential in the service lines energizing the magnets 32—32^a tripping the escapement for a second half of revolution of circuit breaking 115 sector 63, permitting it to break connection with the fingers 61—67, and reestablishing its connection with the break fingers 65. Thus, the service lines may be connected for 120 signal transmission over one of them at 125 130

the central station in a very simple manner. The control of the circuit is also under test under normal conditions which enables the central office to test the circuit control of the transfer device. Any well known means may be employed electrically controlled for rotating the circuit breaking sector to accomplish the result herein set forth.

Having described my invention, I claim:

1. In a signal system, comprising a complete metallic line, a source of current having one pole thereof connecting with said metallic line and the opposite pole grounded, a resistance interposed in said line, a ground connection between the ends of the resistance dividing said metallic line into independent service circuits having an earth return, a relay for each service line in circuit therewith and connected in series circuit connection with said metallic line, and a circuit controller for shunting said resistance and cutting out the earth return.

2. In a signal system, comprising a metallic line, a source of current having one pole thereof connecting with said metallic line and the opposite pole grounded, a resistance interposed in said line, signal transmitting apparatus in circuit with said metallic line, a grounded connection interposed in said resistance between the ends thereof for dividing said metallic line into independent circuits, each having an earth return, a relay for each service line in circuit therewith, and electro-magnetic means having its magnet windings normally in circuit with said independent service lines for shunting said resistance and establishing a unitary metallic line.

3. In a signal system, comprising a metallic line having its ends connecting with a common pole of a source of electric current, a source of current having one pole grounded, transmitter and receiving devices in series circuit connection with said metallic line, a resistance in said line, and a switch device having one pole connecting with said resistance intermediate of its ends, and an opposite pole grounded for dividing said line into series circuit with the ground return and alternately for shunting said resistance.

4. In a signal system, comprising a metallic line, a source of current having one pole thereof connecting with the ends of

said metallic line and the opposite pole 55 thereof grounded and earth connection for said line for dividing said metallic line into independent circuits, each having an earth return, signal transmitting apparatus for each independent circuit in circuit therewith, receiving apparatus for each independent circuit in circuit therewith, and electro-magnetic means having its magnet windings normally in circuit with said independent service lines for cutting out said earth connection and establishing a unitary metallic line.

5. In a central station signal system, a pair of metallic circuit lines extending from the central station for a partial circuit, having a common earth return connection, a source of current having one pole thereof connecting with one end of said circuit lines, and its opposite pole grounded, a resistance respectively for each of said service lines, 75 signal transmitting apparatus respectively for each metallic circuit line having a normally open ground connection adapted to connect with the metallic line for shunting said resistance, whereby distinguishable 80 signals may be transmitted to the central office by the same piece of apparatus, and a switch device for establishing said common earth return connection for and alternately connecting said circuit lines.

6. In a signal system, a plurality of signal metallic lines, each having a resistance and ground return, a source of current having one terminal connecting with said metallic lines and its opposite terminal grounded, a 90 plurality of signal receiving relays operated by different strengths of current, for each line, signal transmitting devices having a ground connection adapted when cut in circuit with said line to shunt said resistance for changing the current strength for successively operating said relays, and a switch device for said metallic lines for connecting said lines to a ground return 100 and alternately breaking said ground return and connecting said metallic lines.

In witness whereof, I hereunto subscribe my name, as attested by the two subscribing witnesses.

ALFRED E. MEYER.
